JACOB WEINSTEIN, OF NEW YORK, N. Y., ASSIGNOR, BY MESNE ASSIGNMENTS, TO JIFFY-ALL CORPORATION, OF NEW YORK, N. Y., A CORPORATION OF NEW YORK.

GARMENT-PROTECTOR.

1,284,510.

Specification of Letters Patent. Patented Nov. 12, 1918.

Application filed February 8, 1918. Serial No. 216,128.

To all whom it may concern:

Be it known that I, JACOB WEINSTEIN, a citizen of the United States of America, and a resident of the borough of Manhattan 5 of the city of New York, in the county and State of New York, have invented a certain new and useful Improvement in Garment-Protectors, of which the following is a specification.

10 My invention relates to the class of garment worn over the customary clothing for protection against soiling or for sanitary purposes, and the object of my invention is to provide a garment which may be quickly 15 adjusted and removed, and one which will afford ventilation and freedom of movement, and afford the same protection as aprons, overalls and the like.

With these objects in view I have designed 20 a garment embodying the features of both aprons and overalls, and giving more protection to the clothing than an apron, and avoiding the objectionable features of overalls. That is to say, my improved garment 25 is as readily adjusted as an apron and avoids the necessity of drawing it over the customary clothing as in the case of overalls, and avoids the overheating due to a complete encircling garment, and further- 30 more it may be more quickly removed.

The improved garment comprises two leg pieces, two bib pieces, two buttock pieces and a waist-band. The leg pieces are cut straight at the waist-line and outside edge, 35 and the inside edge from waist-line to crotch has an inward curve, while from the crotch to the bottom the inside edge may be cut straight or slightly curved. These pieces are joined together only at the front from 40 waist-line to crotch along the curved cut, the projecting portion being designed to fit into the crotch of the wearer. The bib pieces are cut straight on the waist-line and the two edges which are joined together with 45 a vertical seam are cut with a slight outward curve to conform to the chest of the wearer. The top edge may be cut straight or curved with a slant to the waist-line. The buttock pieces are cut to cover the buttocks with an 50 overlap at the seat so as to give complete protection both when the wearer stands erect or when stooping or seated, and the length of these pieces extends from waist-line to the knees. I prefer to cut these pieces so as 55 to have three sides or edges; a short straight

edge for joining to the bib piece at the waist-line, a long curved edge having a slight outward curve for joining to the leg piece, the curve imparting contour to the buttock piece, and the third or free edge having a deep 60 outward curve. A waist-band overlaps the seam of the bib, leg and buttock pieces at the waist-line, and the band is provided with any form of quick or snap fastener. No shoulder straps are provided for the bib, 65 but to guard against the bib slipping down I provide one or more stays, preferably two flat steels jointed together in V-shape and attached to the bib with the joint under the waist-band. The leg pieces are each provided with flat curved spring bands which are inserted in the bottom hems to encircle 70 the legs of the wearer at the ankle, and which, when the garment is adjusted, cause the leg pieces to surround the legs of the 75 wearer and produce the appearance of trousers or overalls.

In the accompanying drawing which illustrates my invention, Figure 1 is a front view of the garment as it appears when worn over 80 the customary clothing, and Fig. 2 a back view. Fig. 3 is a plan of the main pieces employed in making the garment; Fig. 4 a plan view of the belt piece; Fig. 5 a view of the bib supporting stays; and Fig. 6 is a 85 perspective of the spring leg bands.

Referring to Figs. 1 and 2 of the drawing, 1 indicates the leg pieces sewed together at the middle front from waist-line to crotch; 2 indicates the bib cut in two similar shaped 90 pieces sewed together at the middle and to the leg pieces at the waist-line. 3 indicates the two hip or buttock pieces sewed into the angle formed by the leg and bib pieces. Over the seam joining the bib, leg and buttock pieces at the waist-line is sewed the waist-band 4. This band at one end is provided with large eyelets 4^a, three being shown, and the other end is provided with a pivoted lever clasp, 4^b, the lever of which may be inserted into either of the eyelets. This is the preferred form of fastener, but any other quick acting form of fastener which will hold securely when closed may be employed. The bib has loosely attached to it a pair of stays 5, which are covered and held in place by strips 6. The stays are preferably curved slightly to conform to the chest of the wearer and are hinged together in V-shape and the joint being seated under 100 105 110

the waist-band. The ends of the stays are covered with guard 7 of light leather or other suitable material to reduce wear on the material of the garment pieces. The 5 purpose of stays 5 is to hold the bib extended against the chest of the wearer and prevent sagging, and by placing them loosely in the pockets formed by strips 6, they are free to adjust themselves flat to the body of the 10 wearer when the waist-band is closed. At the bottom of the leg pieces curved flat spring bands 8 are inserted in the hems which normally hold the ends in overlapped circular form and which permit the leg 15 pieces to be quickly adjusted to the wearer and cause the leg pieces to encircle the trousers of the wearer, thus presenting the appearance of trousers or overalls.

The shapes of the bib, leg and buttock 20 pieces are shown in Fig. 3 where they are shown in the relative positions before being joined together. The proportions and shape of the several pieces may be varied to meet garment sizes or other requirements. I may 25 also cut the right and left bib parts in one piece with the right and left leg parts, respectively. In such case, however, I would not have the extreme end of the bib part project beyond the outside edge of the leg 30 part, but would cut it as indicated in dotted lines at the left of Fig. 3. In such case the bib and leg parts would be joined on the same curves as indicated, and the buttock pieces would be attached to the leg parts as 35 already indicated.

What I claim is:—

1. An apron-like garment comprising a pair of leg pieces joined together from waist-line to crotch, a waistband joined to the leg 40 pieces and provided with a fastener, two buttock pieces joined to said leg pieces and waist-band, extending approximately from waist-band to knee, and having a width across the buttocks to give overlap and tapering toward the knee, and curved spring 45 bands at the bottom of the leg pieces to close same about the legs of the wearer, whereby the garment may be quickly adjusted and removed, and when adjusted resemble 50 trousers.

2. An apron-like garment comprising a bib having its sides cut with a backward slant to the waist-line, a pair of leg pieces joined together from waist-line to crotch, 55 and at the waist-line joined to the bib, two buttock pieces joined to the leg pieces, extending approximately from waist-line to

knee, and said pieces being cut with an outward curve along the edges which are joined to the leg pieces, thereby giving contour to 60 said parts, and the free edge curving outward from the waist-band to a width giving overlap across the buttocks and then curving inward to the knee, a waist-band covering the seam joining the bib and leg pieces and 65 provided with a fastener, a pair of stays for the bib hinged together flatwise in V-shape and curved lengthwise, and curved spring bands inserted in the hems at the bottom of the leg pieces for closing same about the legs 70 of the wearer, whereby the garment may be quickly adjusted and removed, and when adjusted resemble trousers.

3. An apron-like garment comprising right and left bib, leg and buttock pieces, the 75 right and left pieces of the garment being joined together from top of bib to leg crotch, the right and left bib pieces being joined on outwardly curved cuts, the leg pieces being joined on inwardly curved cuts 80 extending from waist-line to crotch, and the buttock pieces being cut with a short straight edge where joined to the bib pieces, a long outwardly curved edge where joined to the leg pieces, thereby giving contour 85 to said parts, and the free edges curving outward from the waist-band to a width giving overlap across the buttocks and then curving inward to the knee, a waist-band covering the seam joining the bib and 90 leg pieces and having a pivoted-lever fastener at one end and one or more eyelets at the other end, a pair of flat stays hinged together in V-shape and curved lengthwise, a covering for the three ends of the stays, and 95 said stays being loosely inserted in pockets on the bib pieces with the hinged ends seated under the waist-band and whereby said stays are free to adjust themselves longitudinally and laterally for spreading and holding the bib to the chest of the wearer, and curved spring bands inserted in the hems at 100 the bottom of the leg pieces for closing same about the legs of the wearer, whereby the garment may be quickly adjusted 105 and removed, and when adjusted resemble trousers.

This specification signed and witnessed this 25th day of January, 1918.

JACOB WEINSTEIN.
